UNITED STATES PATENT OFFICE.

JOHN LEWIS AND FREDERICK A. BROWN, OF BOSTON, ASSIGNEES TO THEMSELVES AND EDWARD CUNNINGHAM, OF EAST MILTON, MASS.

MARINER'S COMPASS.

SPECIFICATION forming part of Letters Patent No. 247,505, dated September 27, 1881.

Application filed June 27, 1881. (No model.)

To all whom it may concern:

Be it known that we, JOHN LEWIS and FREDERICK AUGUSTUS BROWN, of Boston, of the county of Suffolk and State of Massachusetts, have invented a new and useful Improvement 5 in Mariner's Compasess; and we do hereby declare the same to be described in the following specification and represented in the accompanying drawings, of which—

Figure 1 is a top view, Fig. 2 a bottom view, and Fig. 3 a transverse section, of a compass card and float provided with our invention, which has special reference to the cards and floats of what are termed "liquid compasses."

We have found in practice that a floatable compass-card and its magnetic needle, having a series of sets of U-shaped magnets arranged on the lower surface of the float (or a 20 plate fixed thereto) and at or near the periphery of the float, though capable of effectually resisting local attraction, is liable at times to be somewhat sluggish in its movements, and not always to be depended on for accurate polarity, such being due to the friction and resistance resulting from the edges of the needle, the magnets, and the float in moving in the fluid in which they may be placed. To obviate this difficulty we employ, with the float 25 and its needle and sets of U-magnets, an auxiliary magnetic needle, which we extend across the float, or in or over its upper side or part, or between such and the card when the latter is used.

In case of the divisions and points of the card being marked directly on the upper surface of the float, the separate card or disk having such divisions or marks upon it would not be needed.

We have found that the above arrangement of the auxiliary needle is better than to place it immediately underneath the float and in the plane of the U-magnets, or to increase the depth of the main needle, in order to increase 45 its magnetic force, for in these latter cases there seems to be produced, from some unknown cause, an impediment to the proper action of the magnet to overcome local attrac-

tion; but when the auxiliary needle is used and is arranged above the float, and thus out 50 of the circle of the magnets, not only is very quick and accurate polarity obtained, but the ability of the sets of U-magnets to resist local attraction is not impaired. Besides, by making the card with a central opening and 55 extending the auxiliary magnetic needle across such diametrically in the meridian-line of the card, the needle serves as a guide for the mariner readily to distinguish the north and south points of the meridian-line from their flanking-points.

In the drawings, A denotes the float; B, the main magnetic needle; C C, &c., the series of sets of U-magnets; D, the auxiliary magnetic needle; and E, the card or disk marked 65 with the points of the compass and having a circular opening, a, at its center, all being arranged as set forth.

A hollow conical standard, b, open at its lower end and erected on the bottom of the 70 float, serves to support the pivotal bearing or step of the float, which may be screwed or fixed into such standard and go through the auxiliary needle at its middle, and aid, with the standard, in holding such needle in place. 75

We prefer to have the compass-card made of glass with a colored vitrified surface, such surface in the spaces between the points being removed by fluoric acid, so as to form the points from such colored surface. In such case 80 the glass card is not liable to be injured by the alcohol or fluid generally employed in the bowl of the compass.

We claim as our invention as follows, viz:

1. The combination of the float and its magnetic needle and sets of U-magnets arranged below or against the bottom of such float with the auxiliary magnetic needle disposed above the float or applied to the upper part or top thereof, all being substantially as set forth. 85 90

2. The combination of the open compass-card, the float, the main and auxiliary magnetic needles, and the sets of U-magnets, arranged and combined substantially as described and represented. 95

3. The combination of the float and its cen-

tral tubular standard with the main and auxiliary magnetic needles and the sets of U-magnets arranged with such float and standard, substantially as set forth.

5. The combination of the float, the tubular standard, the open compass-card, the main and auxiliary magnetic needles, and the sets of U-

magnets, arranged and adapted substantially as shown and described.

JOHN LEWIS.

FREDERICK AUGUSTUS BROWN.
